(57) **CLAIM**

We claim the ornamental design for a marker cartridge, as shown and described.

DESCRIPTION

FIG. 1 is a perspective view of a marker cartridge showing our new design;

FIG. 2 is a side view of the marker cartridge of FIG. 1; FIG. 3 is a front view of the marker cartridge of FIG. 1; and, FIG. 4 is a rear view of the marker cartridge of FIG. 1. The broken lines represent portions of the marker cartridge that form no part of the claimed design.

1 Claim, 4 Drawing Sheets
